(57) CLAIM

I claim the ornamental design for a set of seating furniture, as shown and described.

DESCRIPTION

FIG. 1 is a Perspective view of a set of seating furniture showing my new design;
FIG. 2 is a Front view thereof;
FIG. 3 is a Back view thereof;
FIG. 4 is a Left-side view thereof;
FIG. 5 is a Right-side view thereof;
FIG. 6 is a Top view thereof; and,
FIG. 7 is a Bottom view thereof.

The broken lines in the drawings depict portions of the set of seating furniture that form no part of the claimed design.
